AUTOMOBILE FLOOR MAT

Charles A. Wells and Raymond A. Krusinski, Coshocton,
Ohio, assignors to Pretty Products, Inc., Coshocton,
Ohio

Filed July 2, 1971, Ser. No. 159,576

Term of patent 14 years

Int. Cl. D6—11

U.S. Cl. D14—5

FIG2

FIG3

FIG5

FIG6

FIG9

FIG. 1 is a top plan view of an automobile floor mat embodying this invention.

FIG. 2 is an enlarged top plan view of a fragmentary portion of the textured surface area of FIG. 1.

FIG. 3 is a vertical sectional view on an enlarged scale taken along line 3-3 of FIG. 1.

FIG. 4 is a vertical sectional view on an enlarged scale taken along line 4-4 of FIG. 1.

FIG. 5 is a vertical sectional view on an enlarged scale taken along line 5-5 of FIG. 1.

FIG. 6 is a vertical sectional view on an enlarged scale taken along line 6-6 of FIG. 1.

FIG. 7 is a vertical sectional view on an enlarged scale taken along line 7-7 of FIG. 1.

FIG. 8 is a vertical sectional view on an enlarged scale taken along line 8-8 of FIG. 1.

FIG. 9 is a vertical sectional view on an enlarged scale taken along line 9-9 of FIG. 1.

FIG. 10 is a vertical sectional view on an enlarged scale taken along line 10-10 of FIG. 1.

It is to be understood that the textured pattern which is partially shown in FIG. 1 for convenience of illustration is understood to cover the entire surface in which the partial pattern is shown.

We claim:

The ornamental design for an automobile floor mat, as shown and described.
